CLAIM

The ornamental design for a sports training device, as shown and described.

DESCRIPTION

FIG. 1 is a top isometric view of a first embodiment of a sports training device.

FIG. 2 is a fragment enlarged view taken on box 2 of FIG. 1.

FIG. 3 is a left end view of the device of FIG. 1.

FIG. 4 is a right end view of the device of FIG. 1.

FIG. 5 is a back side elevation view of the device of FIG. 1.

FIG. 6 is a front side elevation view of the device of FIG. 1.

FIG. 7 is a right side elevation view of the device of FIG. 1.

FIG. 8 is a left side elevation view of the device of FIG. 1.

FIG. 9 is an exploded perspective view of FIG. 1 including the broken line showing of optional weights.

FIG. 10 is a perspective view of FIG. 9 with the broke line optional weights attached.

FIG. 11 is another top isometric view of the device of FIG. 1; and,

FIG. 12 is a fragmented enlarged view taken on box 12 of FIG. 11.

The evenly spaced broken lines indicate portions of the sports training device that form no part of the claimed design. Portions of the claimed design are shown by dash-dot-dash broken lines and separated and bound by a bracket indicate indeterminate length.
